UNITED STATES PATENT OFFICE.

FREDERIC E. BAGER, OF KENOSHA, WISCONSIN, ASSIGNOR TO FREDERICK C. AUSTIN,
OF CHICAGO, ILLINOIS.

CAR FOR MOVING MATERIAL FROM TUNNELS.

1,201,429.

Specification of Letters Patent.

Patented Oct. 17, 1916.

Application filed February 7, 1916. Serial No. 76,564.

To all whom it may concern:

Be it known that I, FREDERIC E. BAGER, a citizen of the United States of America, and resident of Kenosha, Kenosha county, 5 Wisconsin, have invented a certain new and useful Improvement in Cars for Moving Material from Tunnels, of which the following is a specification.

My invention relates to dump cars for use 10 in removing the excavated dirt from a tunnel during the operation of tunneling underground.

Generally stated, the object of my invention is to provide an improved dump car 15 especially adapted for this particular purpose.

More specifically considered, the object of my invention is to provide a dump car which will travel outward on one rail, thereby to 20 carry the load to the mouth of the tunnel, which will then dump or discharge the load in a suitable or desired manner, and which will then return upside down on another rail to the inner end of the tunnel.

It is also an object to provide certain details and features of construction and combinations tending to increase the general efficiency and serviceability of a dump car 25 of this particular character.

To the foregoing and other useful ends, my invention consists in matters hereinafter set forth and claimed.

In the accompanying drawings—Figure 1 is a side elevation of a dump car embodying the principles of my invention, showing the same in carrying position on one of the rails of the tunnel. Fig. 2 is a cross-section of the said tunnel, on a smaller scale, showing the said dump car in end elevation.

Fig. 3 is a similar view showing the dump car in the position in which it is maintained while returning from the mouth of the tunnel to the inner end of the latter or the place where the dirt is being excavated.

As thus illustrated, the tunnel is preferably round in cross-section, as shown in Figs. 2 and 3, and is provided along the bottom thereof with parallel rails A and B which are spaced a suitable distance apart 50 and which may be of any suitable character.

The dump car has a body C provided with a flat open top c and a flat inner side wall 1, which latter extends at right angles to the said top. The outer side 2 of said body 55 is curved to enable the car to travel close to the side of the tunnel, and this side is provided with a door D of any suitable character, hinged at its upper edge at d to the upper portion of the body, whereby the contents of the car may be dumped or discharged in the desired manner. The bottom of said body is provided with front and rear wheels E which travel on the rail A while the car is moving with its load toward 60 the mouth of the tunnel. The outer side of said body is provided with front and rear rollers F which travel on the sides of the tunnel, thereby to hold the car in carrying position. Said body is also provided with 65 front and rear wheels G which are carried on swinging legs g, the latter being connected by links 3 with the brackets 4 on the ends of the body. Hooks H are pivoted on said legs at h and adapted at their other 70 ends to engage the pins 5 on the ends of the body. In this way, the said hooks support the wheels G in elevated positions while the dump car is traveling toward the mouth of the tunnel with its load. After the car 75 reaches the outer end of the tunnel, and after the load has been discharged or dumped, the body C is then inverted or turned upside down, as shown in Fig. 3, and the wheels G are brought into engagement 80 with the rail B, thereby to support the body in the manner shown. This may be accomplished by disengaging the hooks H from the pins 5 and then causing them to engage the pins I, the rollers F at this time engag- 85 ing the other side of the tunnel. In this position, the dump car is adapted to travel back from the mouth of the tunnel to the place where the dirt is being excavated.

With this construction several dump cars 95 can be traveling outward along the tunnel at the same time that several other dump cars are traveling or returning to the inner end of the tunnel, the outgoing cars freely passing the incoming cars. Each car, after 100 reaching the mouth or outer end of the tunnel, is then transferred from the rail A to

the rail B, without turning the car around or reversing it end for end, and by simply turning it upside down.

Any suitable means, such as the conveyer 5 J indicated in Fig. 1, may be employed for delivering the excavated dirt to the dump cars.

It will be understood, of course, that the dump cars thus constructed can be manipulated by hand, being designed more especially for use in small tunnels, and that they can be propelled in any suitable manner. The flat inner side 1 of the dump car body is always substantially at the center of the 15 tunnel, regardless of whether the car is upside down or in carrying position, but the vertical plane side wall 1 is a little to one side of the center of the tunnel when the car is in carrying position, and a little to 20 the other side of the center when the car is in returning position, whereby the cars on one rail do not interfere with the cars traveling in the opposite direction on the other rail.

25 It will be understood, of course, that any suitable arrangement can be employed for keeping the wheels G out of the way, substantially as shown in Fig. 2, while the dump car is traveling with its load toward 30 the mouth of the tunnel. As shown, the additional pins 5 are employed for this purpose; but it will be possible, of course, to do this in other ways. For example, the parts 35 may be so proportioned that the hooks H may engage the pins I in both positions of the body; so that the pins 5 will not be necessary. Or, if desired, stops or lugs may be located on the ends of the body C in such a manner that the wheels G may, by arranging 40 said stops or lugs to engage the links 3 or the legs g or the hooks H, be held in any position which will keep them clear of the ground and out of the way while not in use.

With further respect to the door or swinging side D, a hinge K can be provided at a 45 point between the upper and lower edges of said door, preferably adjacent the lower edge, whereby the said door will be composed of two sections. In unloading the car, 50 the lower section of the door can first be swung outward about its hinge K, and the entire door can then be swung outward about its upper hinge d. With a door composed of one rigid section, it would be liable to strike 55 the ground at its lower edge when opened. But by using a door composed of sections hinged together in the manner shown and described, the door can be opened with less liability of striking the ground at its lower edge. Any suitable means can be employed 60 for locking or holding the upper section of the said door in closed position while the short lower section is being opened, should such be found necessary or desirable.

65 As shown, the wheels E and G, and also

the rollers F, are employed only at the ends of the car. It will be understood, however, that these rotary supporting elements can be located on the body in any suitable or desired manner.

I do not limit myself to the exact construction shown and described.

What I claim as my invention is:

1. A dump car comprising a body provided with wheels traveling on a single rail 75 to support the load only at one side of the center of gravity thereof, so that the car tends always to tip laterally toward the other side, means on said other side of the body to travel on a suitable support and thereby hold the body in carrying position, and wheels to support the body upside down on another single rail.

2. A dump car comprising a body provided with wheels to support the load only 85 at one side of the center of gravity thereof, so that the car tends always to tip laterally toward the other side, and means on said other side of the body to travel on a suitable support and thereby hold the body in carrying 90 position, the side of the body nearest said wheels being substantially flat and vertical, the other side of said body being curved upward from said wheels to said means, whereby said dump car is adapted to 95 travel within a tunnel and at one side of the center thereof.

3. A dump car comprising a body provided with wheels to support the load only 100 at one side of the center of gravity thereof, so that the car tends always to tip laterally toward the other side, means on said other side of the body to travel on a suitable support and thereby hold the body in carrying position, and other wheels arranged for supporting the body upside down, said means being disposed in position to maintain the stability of said body in both positions thereof.

4. A dump car comprising a body provided with wheels to support the load only 110 at one side of the center of gravity thereof, so that the car tends always to tip laterally toward the other side, and means on said other side of the body to travel on a suitable 115 support and thereby hold the body in carrying position, said wheels having horizontal axes of rotation, the said means consisting of rollers having vertically disposed axes of rotation, and a single rail for said rollers, 120 said rollers being arranged in position to engage the side of a tunnel which is round in cross-section and along the bottom of which said rail is disposed at one side of the vertical plane of the axial center of said tunnel 125 and the entire car being at this side of said plane.

5. A dump car for use in a tunnel which is round in cross-section, and in which a two-rail track is laid along the bottom thereof,

comprising a body provided with wheels for supporting it in carrying position on one of said rails, thereby to carry the load of dirt to the mouth of the tunnel, and provided with other wheels for supporting said body upside down on the other rail, the car on one track being adapted to pass a similar car on the other track when the body of one car is upside down and the body of the other car is 10 in carrying position.

6. A dump car for use in a tunnel which is round in cross-section, and in which a two-rail track is laid along the bottom thereof, comprising a body provided with wheels for 15 supporting it in carrying position on one of said rails, thereby to carry the load of dirt to the mouth of the tunnel, and provided with other wheels for supporting said body upside down on the other rail, the car on one 20 track being adapted to pass a similar car on the other track when the body of one car is upside down and the body of the other car is in carrying position, said other wheels having articulated connections with the body, 25 and the wheels which support the dump car in carrying position having axes of rotation which are fixed relative to said body.

7. A dump car for use in a tunnel which is round in cross-section, and in which a two-rail track is laid along the bottom thereof, comprising a body provided with wheels for supporting it in carrying position on one of said rails, thereby to carry the load of dirt to the mouth of the tunnel, and provided 30 with other wheels for supporting said body upside down on the other rail, the car on one track being adapted to pass a similar car on the other track when the body of one car is upside down and the body of the other car is 35 in carrying position, said body having axes of rotation which are fixed relative to said body.

8. A dump car for use in a tunnel which is round in cross-section, and in which a two-rail track is laid along the bottom thereof, comprising a body provided with wheels for supporting it in carrying position on one of said rails, thereby to carry the load of dirt to the mouth of the tunnel, and provided 40 with other wheels for supporting said body upside down on the other rail, the car on one track being adapted to pass a similar car on the other track when the body of one car is upside down and the body of the other car is 45 in carrying position, and also in the upside-down position thereof.

9. A dump car for use in a tunnel which is round in cross-section, and in which a two-rail track is laid along the bottom thereof, comprising a body provided with wheels for supporting it in carrying position on one of said rails, thereby to carry the load of dirt to the mouth of the tunnel, and provided 50 with other wheels for supporting said body upside down on the other rail, the car on one track being adapted to pass a similar car on the other track when the body of one car is upside down and the body of the other car is 55 in carrying position, and also in the upside-down position thereof.

10. A dump car for use in a tunnel which is round in cross-section, and in which a two-rail track is laid along the bottom thereof, comprising a body provided with wheels for supporting it in carrying position on one of said rails, thereby to carry the load of dirt to the mouth of the tunnel, and provided 60 with other wheels for supporting said body upside down on the other rail, the car on one track being adapted to pass a similar car on the other track when the body of one car is upside down and the body of the other car is 65 in carrying position.

9. A dump car for use in a tunnel which is round in cross-section, and in which a two-rail track is laid along the bottom thereof, comprising a body provided with wheels for supporting it in carrying position on one of said rails, thereby to carry the load of dirt to the mouth of the tunnel, and provided with other wheels for supporting said body upside down on the other rail, the car on one track being adapted to pass a similar 70 car on the other track when the body of one car is upside down and the body of the other car is in carrying position.

10. A dump car provided with a tilting body, wheels for supporting said body in carrying position, and means including other wheels for supporting said body in an up-side-down position.

11. A dump car provided with a tilting body, wheels for supporting said body in a carrying position, and means including other wheels for supporting said body in an up-side-down position, all of said wheels being in the same vertical plane when the body is inverted.

12. A dump car provided with a tilting body, wheels for supporting said body in carrying position, and means including other wheels for supporting said body in an up-side-down position, said wheels all being 90 adjacent the bottom of the dump car when said body is right-side up.

13. A dump car provided with a tilting body, wheels for supporting said body in carrying position, means including other 100 wheels for supporting said body in an up-side-down position, and means serving to laterally support said body in both positions thereof.

14. A dump car comprising a body provided with wheels to support the load only at one side of the center of gravity thereof, so that the car tends always to tip laterally toward the other side, and means on said other side of the body to travel on a suitable support and thereby hold the body in carrying position, said body having a curved outer side provided with a door hinged at its upper edge and also between the upper and lower edges thereof.

15. A dump car provided with a tilting body, wheels for supporting said body in carrying position, and means including other wheels for supporting said body in an up-side-down position, said body having a 110 curved outer side provided with a door hinged at its upper edge and also between the upper and lower edges thereof.

16. A dump car comprising a body provided with wheels to support the load only at one side of the center of gravity thereof, so that the car tends always to tip laterally toward the other side, means on said other side of the body to travel on a suitable support and thereby hold the body in carrying 125 position.

position, said means consisting of rollers mounted to rotate about vertical axes.

17. A dump car comprising a body provided with wheels to support the load only at one side of the center of gravity thereof, so that the car tends always to tip laterally toward the other side, means on said other side of the body to travel on a suitable support and thereby hold the body in carrying position, said means being disposed adjacent the top of the car and having lateral engagement with said support.

18. A dump car comprising a body pro-

vided with wheels to support the load only at one side of the center of gravity thereof, 15 so that the car tends always to tip laterally toward the other side, means on said other side of the body to travel on a suitable support and thereby hold the body in carrying position, said wheels being disposed practically in line with the side of the car, and said means being disposed in a plane above said wheels.

Signed by me at Chicago, Illinois, this 22nd day of January, 1916.

FREDERIC E. BAGER.
